[57] CLAIM

The ornamental design for a curb sign, as shown and described.

DESCRIPTION

FIG. 1 is an elevational perspective view of my invention and design;

FIG. 2 is a front plan view of the design;

FIG. 3 is an end view taken from the left side of FIG. 1, the right side being a mirror image of the left end view;

FIG. 4 is a top plan view, the bottom view being a mirror image; and,

FIG. 5 is a rear plan view.
